FOLDING CARRIAGE FOR CHILDREN

Luis Gelambla Macip, Barcelona, Spain

Application June 22, 1944, Serial No. 541,623
In Spain July 16, 1943

1 Claim. (Cl. 280—41)

1

The present invention refers to a new folding baby carriage for carrying children in a lying down position, characterized and distinguished essentially from all similar carriages known up to the present, by its extreme lightness, considerable robustness, small size in its used position—which is reduced to the minimum when folded up—and simple construction free from complications, rendering its handling extremely easy.

At the present time there are known a considerable quantity of types of baby carriages for carrying children, and their use is general. These have superseded the old custom of carrying children in arms, with all the inconveniences attached to this custom, but due to their characteristics these carriages in their turn have certain inconveniences. Amongst these may be cited, in the first place, their excessive weight and volume possessed by the majority, making their moving difficult, and above all, their clumsy handling for taking them upstairs and stowing them away in a reduced space.

The above reasons may be the cause occasionally of abandoning these means of transport, as the convenience of their use in the street is offset by the troublesome preparations of bringing them downstairs or getting them out of the place they are kept, troubles which have to be repeated on the return home.

All these troubles are completely avoided by the use of the cot carriage object of this invention, which has the advantage of being foldable, and consequently occupying a small space in this position, at the same time its weight is insignificant, with the fact that it can be easily carried in one hand. Thus there is no difficulty in carrying it upstairs, taking it into lifts, cars, trams, etc., and it is notable also for the small space it occupies when not in use.

The movement for folding or unfolding is extremely simple and does not require any tool or special skill; its joints are solid and cannot be strained by any mean of efforts and the whole offers a complete security and comfort for the child.

Finally, it is to be noted that the placing of the handle has been provided for in such a position that it does not cause any inconvenience, so that the carriage is capable of being used as a cot in the home.

In order to better understand the object of this specification, there is attached a drawing, in which, as an example only, there is shown a practical case of a cot-carriage made up in accordance with this invention.

2

In the drawing, Fig. 1 shows the carriage in side elevation and in a folded position; Fig. 2 shows one of the intermediate positions for opening; Fig. 3 shows it in a position to be pushed along; Fig. 4 is a similar view, but with the handle down for the carriage to be used as a cot; Figs. 5 and 6 are details of the closing or fixing arrangement; and Fig. 7 shows a detail of the principal articulation of the shears.

10 This cot carriage is made up essentially by a double framework in the form of a shears, consisting of the stays 1 and 2 articulated in 3 (see Fig. 7) through the shaft 4 that, forming part of the stay 2 and after passing through the stay 1, projects towards the free side and is surrounded by the helicoidal spring 5 working under compression and held by a washer 6, fixed by a flat plate 21, whose object is to maintain a certain fitting and pressure between both stays. The 20 whole is protected by a small cover 7.

Each of the two pairs of stays 1 and 2 are connected at their bottom ends with cross bars. Each of these cross bars freely rotatably separates at each end one of the wheels 8.

25 The stays 1 on their opposite ends to the wheels 8 are joined in an articulated way to a horizontal frame 9 and in their turn the stays 2 are joined to the said frame, although by means of a set of levers 10 and 10' joinable in the form of 30 a compass. The articulation of the stay 2 with the said levers is carried out by 11, such stay being prolonged and having on its end another articulation 12, shown in detail in Figures 5 and 6.

To this articulation there is joined the lower 35 end of the two branches 13 of the handle, which has at the same time another articulation 14 similar to the 11 of the stay 2, with which it is joined with the said set of levers 10 and 10'.

The horizontal frame 9 has suspended by 40 various helicoidal springs 15 a second cot 16 that holds a net, cloth or something similar, constituting the cot itself.

The handling of this cot-carriage is as follows: Supposing it to be in the position shown in Fig. 1, 45 to open same it is only necessary to separate the handle 13 from the body of the carriage, raising it by the part to be held by the hands, with which movement the articulation of the stays of the said handle 13 with relation to the stays 2 on the 50 axle 12 will cause a progressive separation of the compass formed by the levers 10 and 10' articulated together in 11 and 14 respectively, which will continue opening until the axle of these coincides with that of the articulation 12.

55 This movement will have resulted in a progres-

sive opening of the shears formed by the stays 1 and 2 until they adopt the position shown in Figures 2 and 3.

Once in this position, the last movement of the handle, until it adopts the position of Fig. 4, will not cause any variation of the shears.

In order to close the carriage, there is only necessary a reverse movement of the handle. This will produce the progressive closing of the shears until they again adopt the position shown in Fig. 1.

To fix the handle 13 in the position desired, the articulation 12 (Figures 5 and 6) are provided with a clasp formed by two discs 17 and 18 radially fluted, forming part of the stays 2 and 13, 15 which may remain clutched or unclutched through the action of a threaded shaft 19, forming part of an exterior lever 20.

The whole may be completed with a folding cover and also provided the arrangement of some rings on the handle 13, in order to fix on same some bags to contain clothing or other things.

I claim:

In a folding carriage for children, in combination a frame; a handle; a plurality of stays articulated in the form of sets of shears capable of being closed and opened by movement of said stays, one of the stays of each of said sets of shears being articulated to said frame and the

other of the stays of each of said sets of shears being articulated to said handle; and a set of levers pivoted together in the form of a compass and joining said other stays to said frame so that the pivot of said levers coincides with the articulation of said other stays and said handle, in which position the latter may continue to turn until it is completely depressed.
